Assistant Examiner — Terilyn Davis

CLAIM

The ornamental design for a baby formula dispenser as shown and described.

DESCRIPTION

FIG. 1 is a perspective view of a baby formula dispenser showing our new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view of the baby formula dispenser shown in use; and,

FIG. 11 is a perspective view of the baby formula dispenser shown separately in use.

The broken lines in FIG. 10 and FIG. 11 showing a bottle body and a bottle lid depict environment and form no part of the claimed design. The other broken lines in the drawings depict portions of the baby formula dispenser and form no part of the claimed design.

1 Claim, 11 Drawing Sheets
